CLAIM

We claim the ornamental design for a golf club head, as shown and described.

DESCRIPTION

FIG. 1 is a perspective view of the golf club head as viewed from the rear, above and one side.

FIG. 2 is a front elevation view of the golf club head of FIG. 1.

FIG. 3 is a rear elevation view of the golf club head of FIG. 1.

FIG. 4 is a side elevation view of the toe of the golf club head of FIG. 1.

FIG. 5 is a side elevation view of the heel of the golf club head of FIG. 1.

FIG. 6 is a top plan view of the golf club head of FIG. 1; and, FIG. 7 is a bottom plan view of the golf club head of FIG. 1.

The broken line showing is included for the purpose of illustrating and forms no part of the claimed design. The dash-dot lines are included as boundary lines and form no part of the claimed design. A portion of the crown are stippled heavier and lighter to illustrate contrasting surfaces of different color.
